BENDING DEVICE FOR PIPES AND BARS

Filed June 6, 1928

UNITED STATES PATENT OFFICE

FRED B. POTTER, OF LOS ANGELES, CALIFORNIA

BENDING DEVICE FOR PIPES AND BARS

Application filed June 6, 1928. Serial No. 283,324.

This invention relates to bending devices for pipes and bars, and has for an object the provision of an improved bending device by means of which pipes may be bent without danger of collapsing.

Another object is the provision of a device for bending pipes and bars, which is so arranged as to permit the ready insertion of the article to be bent into the bending apparatus, and which may be operated with a minimum of labor and expenditure of time.

A further object is the provision of a bending apparatus of the general character described, which is provided with a plurality of interchangeable anvils or forms about which the article may be bent so that bends of different radii may be formed in the article.

It is a further object of this invention to produce a bending device provided with an improved type of clamping means whereby the article to be bent may be securely clamped closely adjacent an end thereof to permit bending the article at a point very close to that end.

The invention possesses other objects and features of advantage, some of which, with the foregoing, will be set forth in the following description of the preferred form of the invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings:

Figure 1 is a side elevation of the device constructed in accordance with the invention.

Fig. 2 is a sectional view taken upon the line 2—2 of Fig. 1, with the direction of view indicated by the arrows.

Fig. 3 is a horizontal sectional view taken upon the line 3—3 of Fig. 1, with the direction of view indicated by the arrows.

Fig. 4 is a view similar to Fig. 1, but showing the device as being actuated to bend a piece of pipe.

Fig. 5 is a view similar to Fig. 4, but showing an anvil or bending form of different

size, mounted upon the device to form a bend in the pipe, having a smaller radius.

The device of the present invention is of general application, being adapted to bend all manner of rods and tubes, irrespective of size or material, within certain limits; but the device finds a particular field of utility for electricians' use, since it is peculiarly adapted for bending conduit to the shapes frequently required by electricians in installing conduit preparatory to inserting electric wiring therein. In terms of broad inclusion therefore, the device comprises a body mounted for pivotal movement upon any suitable stationary structure, this body being provided with clamping means for securely clamping one portion of the member to be bent. The body is also provided with an arcuate anvil or bending form about which the article may be bent by swinging the body about its pivotal mounting, there being a stationary member adapted to engage the article at a point spaced from the arcuate member so that as the body is rotated, the article is wrapped around the arcuate surface of the anvil.

Specifically describing the present embodiment, I have provided a body 6 which is connected by means of a pivot pin 7, to a stationary arm 8, for pivotal movement about the pin 7 in respect to the stationary arm. The stationary arm 8 is adapted to be secured to any suitable structure such as a column 9, by bolts 11, lag screws or other suitable fastening means. An anvil is provided in the form of an end member 12; and for the purpose of adapting the bending device to form bends of different radii, the end members 12 are preferably removable and interchangeable; Fig. 5 showing an end member 13 of smaller radius than that shown in Figs. 1 and 4. Each of the end members 12 and 13 is provided with an arcuate surface 14, which, when the associated end member is secured in operative position upon the body 6, is disposed about the pivot pin 7. Preferably, when so positioned, the pivot pin 7 is arranged eccentrically in respect to the arcuate surface 14, being proximal to the upper side 16 of the arcuate surface 14. As a result of

this arrangement, when the body 6 is in the position indicated upon Fig. 1, the uppermost portion of the arcuate surface 14 is lower than the uppermost portion of the arcuate surface 14 when the body 6 is swung to position indicated upon Fig. 4, thus making it easier to insert a pipe 17 or the like into the clamping means when the body 6 is elevated.

10 The end members 12 and 13 are removably securable to the body 6 in any convenient manner such as by a dove-tailed projection 18 upon the body 6, adapted to seat within complementarily shaped notches 19 in the end members 12 and 13 to retain them in operative position. A groove 21 is formed in the arcuate surface 14 of each of the end members 12 and 13, this groove being rounded and of substantially the same radius as the pipe 17 or any other article to be bent.

20 The pipe 17 or the like, which is to be bent, is clamped against the base or body 6 at one end of the grooved end member 12, so that the projecting end of the pipe may be bent around the arcuate surface 14 and into the groove 21 therein provided. The means for clamping the pipe extends tangentially from the proximal end of the arcuate surface 14, and preferably includes a lower jaw 22 rigid with the base 6, and an upper adjustable jaw 23 mounted upon a threaded shank 24 received through a threaded bearing 26 formed upon the upper end of an extension 27 preferably integral with the base 6. An operating handle 28 is provided upon the shank 24 for the rotation thereof, to adjust the position of the jaw 23 in respect to the jaw 22. The shank 24 is swiveled to the adjustable jaw 23; and in order to permit a certain degree of rocking movement of the adjustable jaw in respect to the shank 24, the swiveled connection comprises preferably a pair of plates 31 of resilient metal, each secured at one end to the jaw 23 as by screws 32, and with the other end 33 of each disposed within a groove 34 formed in the lower end of the shank 24.

50 The opposed faces of the jaws 22 and 23 are grooved longitudinally as at 36 and 37 respectively, to facilitate clamping the pipe 17 therebetween. In order to permit grasping the pipe 17 closely adjacent an end thereof, internal threads 38 are formed in that end of the grooves 36 and 37, which is adjacent the arcuate surface 14 of the end member 12 or 13, as the case might be.

55 An extension 41 on the base 6, permits the application of an operating handle or lever 42 by means of which considerable mechanical advantage may be gained to impart rotary movement to the base 6 in respect to the stationary arm 8 about the pivot pin 7. Means for wrapping the pipe 17 about the arcuate surface 14 as the base 6 is so rotated, is provided, preferably in the form of

a pin 43 rigid with the stationary arm 8 at a point spaced from the arcuate surface 14 and supporting a grooved roller 44, the groove 46 of which is in alignment with the jaws 22 and 23 and the groove 21 in the arcuate surface 14.

Since end members 12 and 13 of different sizes are to be employed, I have found it desirable to also employ rollers 44 of different sizes. Accordingly, a larger grooved roller 47 is shown upon Fig. 5, it being intended to employ this larger roller 47 in conjunction with the smaller end member 13. It should be understood however, that it will be fully as effective to employ a single roller 44, but to provide additional sockets for the reception of the pin 43 at various points along the arm 8 so that the roller 44 could be positioned wherever desired in respect to the end member 12 or 13 being employed.

When it is desired to bend a piece of pipe 17 or any similar article, the article is clamped within the grooves 36 and 37 of the jaws 22 and 23 respectively, by tightening the adjustable jaw 23 thereupon. This should be done with the base in the position indicated upon Fig. 1, with the pipe 17 extending from the jaws under the roller 44. Then by exerting force downwards upon the handle 42, the base 6 is pivoted about the pivot pin 7; but since corresponding upward movement of the body of the pipe 17 is prevented by engagement therewith with the roller 44, the pipe 17 will be wrapped about the arcuate surface 14 to produce a bend in the pipe 17, of radius corresponding to that of the end member 12 or 13, depending upon which end member is being employed. It is to be understood of course, that bends of any desired extent may be produced, depending upon the distance through which the base 6 is rotated in forming the bend.

I claim:

1. A bending device comprising a base mounted for pivotal movement about a stationary pivot, an arcuate surface at one end of said base disposed about said pivot, a clamp comprising a jaw rigid with the base and extending tangentially from one end of said arcuate surface, an extension on said base, a shank threaded through said extension, an adjustable jaw swiveled to said shank in register with said rigid jaw, and means permitting rocking movement of said adjustable jaw upon said shank, said jaws being grooved longitudinally to clamp a pipe therebetween, internal threads formed in that end of the grooves of said jaws adjacent the arcuate surface, a stationary pin spaced from said arcuate surface, and a roller carried by said stationary pin in alignment with said jaws.

2. A bending device comprising a base mounted for pivotal movement about a stationary pivot, an arcuate surface at one end of said base disposed about said pivot, a clamp

- comprising a jaw rigid with the base and extending tangentially from one end of said arcuate surface, an extension on said base, a shank threaded through said extension, an adjustable jaw having a recess in the outer face thereof for the reception of the end of said shank, and resilient plates secured at one end of each to said adjustable jaw with the other end of each disposed within a groove in said shank to resiliently retain the end of the shank within the recess, a stationary pin spaced from said arcuate surface, and a roller carried by said stationary pin in alignment with said jaws.
- 5 10 15 20 25 30 35 40 45 50 55 60 65
3. A clamping device comprising a base, a jaw rigid therewith, an extension on said base, a shank threaded through said extension, an adjustable jaw having a recess in the outer face thereof, for the reception of the end of said shank, and resilient plates secured at one end of each to said adjustable jaw with the other end engaging behind a shoulder on said shank to resiliently retain the end of the shank within said recess.
4. A clamping device comprising a base, a jaw rigid therewith, an extension on said base, a shank threaded through said extension, an adjustable jaw having a recess in the outer face thereof for the reception of the end of said shank, and resilient plates secured at one end of each to said adjustable jaw with the other end engaging behind a shoulder on said shank to resiliently retain the end of the shank within said recess, said jaws having opposed grooves extending longitudinally thereof, and internal threads formed in said jaws at one end of said grooves.

In testimony whereof I have signed my name to this specification.

FRED B. POTTER.
